Inventor
Walter I. Kirk
By A. Miller Delford Atty.

UNITED STATES PATENT OFFICE.

WALTER I. KIRK, OF CHICAGO, ILLINOIS, ASSIGNOR TO LYON & HEALY, OF CHICAGO,
ILLINOIS, A CORPORATION OF ILLINOIS.

TUNING-FORK.

1,328,838.

Specification of Letters Patent. Patented Jan. 27, 1920.

Application filed April 4, 1917. Serial No. 159,670.

To all whom it may concern:

Be it known that I, WALTER I. KIRK, a citizen of the United States, residing at Chicago, in the county of Cook and State of Illinois, have invented a certain new and useful Improvement in Tuning-Forks, of which the following is a full, clear, concise, and exact description, reference being had to the accompanying drawings, forming a part of this specification.

10 My invention relates to tuning forks.

One object of the invention is to provide a practical and simple construction of mounted tuning fork.

15 Another object of the invention is to improve the efficiency of the fork and increase the facility with which it is operated.

Another object of the invention is to increase the resonating qualities of the device.

20 In the accompanying drawings Figure 1 is a front elevation partly in section of a tuning fork embodying my present invention;

Fig. 2 is a side elevation of the same; and

25 Fig. 3 is a cross section taken on line 3—3 in Fig. 1.

In the accompanying drawings I show a tuning fork device involving a base member 1 in the form of a hollow drum having feet

30 2—2 on which the device may be supported. The drum 1 is provided with an aperture 3 in the center of its upper wall or top 4. Mounted upon the drum 1 is a frame preferably consisting of two upright members or

35 standards 5—5 located on opposite sides of the central aperture 3. These members 5 are connected to the drum 1 by suitable securing means as for example bolts 6—6 extending through the bottom of the drum and

40 up through the top 4 of the same and provided with projecting threaded ends 7 which

fit into the lower ends of the standards 5. The standards 5 preferably form the lower portions of a supporting structure consisting

45 of said standards 5 and an upper connecting element 8, which is conveniently secured to the members 5 by threaded studs 9 projecting from the members 5. The member 8 supports a tuning fork 10 which extends down

50 between the standards 5 close to the top 4 of the drum 1 so that the lower ends of said fork are in close proximity to the aperture 3. The fork 10 is hung in the connecting piece or top 8 by means of a bolt 12 passing

55 through the upper end of the fork and also

through the walls of said piece 8 and having a nut 14 at one end of the same. The other end of the bolt 12 is preferably made with prongs 15 which serve as supports for a striker 16 having a handle 17 and a striking end piece 18. Thus the tuning fork is suspended in an upright position with unobstructed space on each side so that either prong may be struck and also so that when struck the fork is free to vibrate as much as necessary without striking any other object or article or part of the device. At the same time both prongs are in proximity to the resonator or drum 1 and the air aperture 3 thereof so that the maximum effect may be secured from said resonator.

It will be understood that changes and modifications may be made without departing from the spirit of the invention.

75 What I claim is:

1. A device of the class specified comprising a resonator, a supporting device mounted on the resonator and comprising separated standards or uprights, said resonator having an aperture between said standards, and a tuning fork mounted at the upper ends of said standards and extending downwardly therefrom so that the free ends of the prongs are adjacent said aperture. 80

2. A device of the class specified comprising a resonator having its top provided with an aperture, supporting standards mounted on and rising from the top of said resonator on opposite sides of said aperture, a connecting piece at the upper ends of said standards, and a tuning fork having its upper end attached to said connecting piece and extending downwardly from the same between said supports, the lower ends of the prongs being located above and adjacent to said aperture. 85

3. A device of the class specified comprising a resonator in the form of a vertically arranged cylindric hollow drum having its top provided with a central aperture, uprights having their lower ends resting on the top of said drum on opposite sides of said aperture, bolts extending through the drum and into the lower ends of said uprights for securing the same to the drum, a connecting piece secured to the upper ends of said uprights and connecting the same together, said connecting piece being provided with a socket, a tuning fork having one end set in said socket and having its prongs extending 100

105

110

115

downwardly between said uprights to proximity to the top of said drum, and a bolt extending through said connecting piece and embedded end of the tuning fork for holding the same in position.

4. A device of the class specified comprising a resonator in the form of a cylindric hollow drum having its top provided with a central aperture, uprights having their lower ends resting on the top of said drum on opposite sides of said aperture, bolts extending through the drum and into the lower ends of said uprights for securing the same to the drum, a connecting piece secured to the upper ends of said uprights and connecting the same together, said connecting piece being provided with a socket, a tuning fork having one end set in said socket and having its prongs extending downwardly between said uprights to proximity to the top of said drum, and a bolt extending through said connecting piece and embedded end of the tuning fork for holding the same in position, one end of said bolt being provided with prongs to form a support for a striker.

5. A device of the class specified comprising a resonator, a supporting device mounted on the resonator and comprising separated standards or uprights, said resonator having an aperture between said standards, a tuning fork mounted at the upper ends of said standards and extending downwardly therefrom so that the free ends of the prongs are

adjacent said aperture, and a support for a tuning fork striker also mounted at the upper ends of said standards.

6. A device of the class specified comprising a resonator having its top provided with an aperture, supporting standards mounted on and rising from the top of said resonator on opposite sides of said aperture, a connecting piece at the upper ends of said standards, a tuning fork having its upper end attached to said connecting piece and extending downwardly from the same between said supports, the lower ends of the prongs being located above and adjacent to said aperture, and a support for a tuning fork striker also mounted at the upper ends of said standards.

7. A device of the class specified comprising a resonator, supporting members mounted upon the top of said resonator and extending upwardly therefrom, a tuning fork supported by said supporting members and a support for holding a tuning fork striker, said support being also mounted upon said upwardly extending supporting members.

In witness whereof, I hereunto subscribe my name this 27th day of February, A. D., 1917.

WALTER I. KIRK.
